UNITED STATES PATENT OFFICE

LOUIS H. ZEUN, OF BALTIMORE, MARYLAND

PRINTING MACHINE

Application filed December 23, 1924. Serial No. 757,646.

This invention relates to certain new and useful improvements in printing machines and the process of printing, and has for its particular object the provision of improvements in printing and devices for reproducing a multiplicity of prints arranged in symmetrical relation from a single negative.

The type of printing machines, of which my invention is an improvement, are old and massive, requiring much manual labor to operate and extremely trying on the operators. It is my aim to provide a power-operated means and controls of the same to overcome many of the difficulties of operation and to provide further a new improvement in the existing type of machines and in the process of printing.

Another object of my invention is to provide power-actuated means for positioning a negative on this type of machine.

A further object of my invention is to provide power-actuated means for positioning the plate operated upon.

A further object of my invention is the provision of a locking means to prevent inadvertent movement of the plate while other parts of the machine are being operated upon.

A further object of my invention is the provision of a locking means to lock the negative while other parts of the machine are being operated upon.

A further object of my invention is the provision of a means to lock the negative and plates while other parts of the machine are being operated.

A further object of my invention is the mounting of a plate in an improved manner.

A further object of my invention is the provision of an improved method of holding the plate and its mountings while being operated upon.

A further object of my invention is the provision of means of uniformly contacting said plate with the negative.

A further object of my invention is the provision of electric motors in a machine of the character described, which motors perform various required functions with a minimum number of operations, and the

providing of locking switches and stops to time the motors so as to prevent any inadvertent use of the same.

A further object of my invention is the provision of means whereby the same motors 55 may be used to perform distinct and opposing functions.

A still further object of my invention is the provision of an improved timing means on a plurality of motors, each performing a 60 plurality of functions of opposing characters and arranged at different times to function selectively or individually and locking all other movements in accordance therewith.

With these and other objects in view, my invention consists of the prescribed methods employed, combination and arrangement of systems, apparatus and means, as herein-after specifically provided, illustrated in 70 the accompanying drawings, whereas is shown the preferred embodiment of my invention, it being understood that certain changes, variations and modifications may be resorted to, which come within the scope 75 of the claims hereto appended.

Figure 1 is a plan view of a printing machine as made in accordance with my invention and illustrating the negative slide and curtain in printing position.

Figure 2 is a longitudinal, sectional view in elevation of the machine shown in Figure 1 taken through line 2—2 of Figure 1 with the negative slide and curtain in non-printing position.

Figure 3 is a transverse sectional view taken through line 3—3 of Figure 1.

Figure 4 is an enlarged, longitudinal, sectional view taken on line 4—4 of Figure 3.

Figure 5 is an enlarged view in section taken on a line 5—5 of Figure 2, looking in the direction of the arrow and particularly showing the plate-carrying frame.

Figure 6 is an enlarged detailed view in section taken on line 6—6 of Figure 1.

Figure 7 is an enlarged detailed view in section taken on line 7—7 of Figure 1, looking in the direction of the arrow.

Figure 8 is a sectional transverse fragmentary view taken on line 8—8 of Figure 1, 100

particularly showing the controlling means for the negative slide and operating means.

Figure 9 is a side view in elevation of the operating motor and mechanism for operating the plate holder in a longitudinal direction, which also operates the negative slide. The same Figure 9 is a view representing a single unit for operating the plate holder transversally and the raising and lowering of the plate-holding frame, the prime numerals representing the latter functions.

Figure 10 is a plan view of that shown in Figure 9.

Figure 11 is an enlarged view in section of the indexing handle and control switch, illustrated in Figure 9.

Figure 12 is an enlarged sectional view taken on line 12—12 of Figure 2, looking in the direction of the arrow and showing particularly the negative slide, the stop for the same, and the means of supporting the curtain.

Figure 13 illustrates the fastening of the curtain to the negative slide.

Figure 14 is an enlarged, sectional view taken on line 14—14 of Figure 2, and,

Figures 15 and 16 are diagrammatic views of the wiring control.

Referring to the drawings, the numeral 1 indicates a table or bed, preferably made of cast iron or other metal suitable for the purpose and supported on legs 2, and this table is provided with a central opening 3, through which the exposure of a negative can be made.

Slidably mounted upon the table to definitely travel longitudinally thereon, is a negative slide 4, which is adapted to be moved to a definite position over the opening 3 and back to its initial position so that a negative 6 may be changed.

Secured to the negative slide 4 is a curtain 5, and this curtain 5 freely moves with the negative slide 4 and protects the rear end of the negative slide from light, and the other end being protected by an inserted deck in that portion of the table 1. The negative 6 is the means through which exposures are made and it is mounted on the negative slide 4 in the usual manner.

A sensitized printing plate 7 is provided and this plate is mounted on a rubber-coated board 8 by rubber cement or other suitable means, and this board 8 is secured to a frame 9 by bolts or other suitable fastening means. The frame 9 is secured in a plate-holding frame 10, in which operates the board-holding bar 11, and to this bar 11 is secured the board-holding frame 9 by screws or other suitable fastening means, (see Figure 5); and the opposite sides of this board frame operate in a groove 12.

The supporting bar 11 is provided with rack-teeth 13 on its central portion, and

these rack-teeth mesh with the pinion 14 mounted on a vertical shaft 14^a, and this affords an auxiliary hand adjusting means for the plate when in longitudinal movement.

The plate-holding frame 10 is suspended by a plurality of bearing boxes 15, (see Figures 1, 3, 4, and 7), in which boxes operate cam 16, which construction provides a positive means of vertically operating the plate-holding frame 10 relative to the table 1.

The plate-holding frame 10 is supported by a top frame 17 by means of guides 18 and the cams 16, and this top frame 17 is supported by a bottom frame 20.

Secured to the plate-holding frame 10 are compensating guides 19 on two sides thereof, and these guides 19 operate against guides 18, so as to take up any movement that may be between the frames, the other two sides remaining in direct contact with their respective supports.

Mounted on the top frame 17 are shafts 21, on which shafts are secured the cams 16, and these shafts are provided with worm gears 22, which gears are driven by suitable worms 23 and the worms 23 are driven by spline shafts 24, as will be clearly shown from the drawings. The cams 16 operate in suitable bearing boxes 15, which bearing boxes are constructed to allow for a considerable movement therein.

The bottom frame 20 is supported on and operates over table 1, and this frame is guided in the usual way by a guide 25 on one side, and has mounted on its free side, rollers 26, and this frame is movable longitudinally over said table by any suitable means such as a screw 27 operating in a nut 28. The bottom frame 20 may be locked in any fixed position on table 1 by means of a rod which is secured at one end to the table by suitable fastening means such as is shown at 30. This rod is slidably mounted on brackets 31 carried by the bottom frame 20 and is provided with a locking means 32, which permits the frame to be locked in any fixed position relative to the table.

The top frame 17, previously described, operates on the bottom frame 20 and is guided thereon in the usual way by guides 33 on one side and rollers 34 on the opposite side, and this frame is operated on said bottom frame in a transverse direction by any desirable means, such as a screw 35 and a nut 36.

The top frame 17 can be locked in any fixed position relative to the bottom frame 20, by means of a rod 37, which is secured at one end to the top frame 17 and movable therewith, and this rod 37 operates through a bracket 38 which is secured to the bottom frame 20, and this bracket is provided with a suitable locking means 39 so as to lock the frame in fixed position, as described.

Arranged below the central opening 3 of

the table 1 is the usual light shutter 40 and this opening is located below the negative slide supporting rail.

Secured to the table 1 are two brackets 41 and 42, which carry and upon which operates a beam 43, this beam being adjustably operated transversally of the table, by means of a rack 44 and pinion 45, said pinion being operated by hand by means of a shaft 46.

10 The beam 43 has operatively mounted thereon a pressure head 47 through the medium of a knuckle joint 48 and a plunger 49, which plunger operates between adjustable definite limits by means of links 50, bell crank 51, connecting rods 52, and bell crank 53. The bell crank 53 is provided with a handle which is mounted on adjustable bearings 54, which bearings are adjusted by means of an adjusting screw 55 and nut 56, said bell crank 53 being suitably mounted on beam 43.

Secured to the negative slide is an endless chain 57 operating over a loose sprocket wheel 58 and a driving sprocket wheel 59. 25 The sprocket wheel 59 is mounted on a shaft 60 and by means of a reduction worm gear is driven by sprocket 61, which sprocket may be manually operated when desired by applying a crank to the shaft upon which it is mounted. The sprocket wheel 61 is driven by sprocket wheel 62 carried on shaft 63, and sprocket wheel 64 is mounted on a clutch sleeve 65, which drives shaft 63 by means of clutch 66 operated by handle 71.

35 The sprocket wheel 64 is driven by sprocket wheel 67 mounted on shaft 68, which shaft is driven through suitable reduction gearing 69 by the motor 70, as will be clearly seen in Figures 9 and 10.

40 The bottom frame 20 is operated by screw 27, which screw is driven by gears 72, which gears are in turn driven by clutch gear 73 loosely mounted on shaft 68 and operated by clutch 74 carried on the same shaft, and 45 this clutch 74 is engaged and disengaged by a lever 75. The screw 27 is also provided with a hand-operated means 76.

The plate-holding frame 10 can be vertically operated by means of the spline shaft 50 24, which shaft is driven by a sprocket wheel and clutch 64^a, 65^a and 66^a, which are similar to sprocket 64, clutch sleeve and clutch 66, (See Figure 10), and these two driving mechanisms are substantially identical. The spline shaft 24 is also provided with means of manual operation 77, which is a square-ended shaft to which a handle may be attached.

55 The top frame 17 is operated transversely by means of a screw 35 and nut 36, and this screw and nut are similarly operated to screw 27 by a motor 70^a and this screw 35 is also manually operated in a manner similar to screw 27.

65 Referring to Figure 11, either shaft 27

or 35, depending upon which unit is considered, is attached to operating crank 95, this crank carrying operating handle 76 and index pin 96, commutators 81 and 82, and switches 1' or 2', which also depends upon which unit is being considered.

The index pin 96 operatively registers an index plate 97 at points desired, thus pre-determining the required movements. This pin 96 is held in open position by a pin 98, which engages in a suitable slot or catch, and the index plate 97 is relatively fixed with relation to the table 1. To lock the negative slide 4 in printing position, I provide two levers 88 and 89, as illustrated in Figure 2, and these are mounted on a common shaft 90 and positioned to lock the negative slide 4 near each edge. Secured to the levers 88 and 89, near the ends are adjusting screws 91 and 92, and these screws bear against the back end of the negative slide when the same is in position and lock it therein. The shaft 90 is operated by a lever 93 and an adjustable connecting rod 94, and a crank attached to a hand lever 87.

Having thus described the principal mechanical features of a printing machine involving my improvements, I will now endeavor to particularly point out the various controls of the machine and details concerning the same.

Referring to the negative slide control, and presuming the slide is in a printing position, the following conditions must exist before it can be moved:

(a) The plate-holding frame 10 must be up;

(b) Clutch 74 for operating screw 27 must be out, or free;

(c) Locking device for negative slide must be released;

(d) Clutch 66 must be in;

(e) The movement of the carriage out or back to charging position is then controlled by a reverse starting switch.

(f) To return the negative slide to printing position a similar condition must exist, except the forward starting switch is used.

These various switches and stations will be described later.

To operate the bottom frame the following conditions must exist:

(a) Index pin 96 must be free of dial 97;

(b) Plate-holding frame 10 must be up;

(c) Locking means 32 must be released;

(d) Pressure head 47 must be up;

(e) Clutch 66 must be out, or open;

(f) Clutch 74 must be in. Then, by pushing either the forward or reverse starting switches, the frame may be operated in either direction.

To operate the top frame 17 the following conditions must exist:

(a) The index pin 96^a must be free of the dial 97^a;

- (b) Plate-holding frame 10 must be up;
  - (c) Locking means 39 must be released;
  - (d) Pressure head 47 must be up;
  - (e) Clutch 66^a must be open;
  - (f) Clutch 74^a must be closed, or engaged.
- 5 Then top frame may be operated in either direction by forward or reverse starting switches as desired.

10 The plate-holding frame 10 may be operated vertically, if the following conditions exist:

- (a) Clutch 74^a, which operates screw 35, must be out, or open;
  - (b) Pressure head 47 must be up;
  - (c) Clutch 66^a must be in, or engaged;
- 15 then the pressure head may be raised, or lowered, as desired, by the forward or reverse starting switches.

20 The various functions above enumerated are performed manually, the machine automatically locking the various parts until the conditions enumerated exist; and, further, the various parts are automatically stopped at the limit of various travels.

25 I will now proceed to more particularly point out the automatic features involved in the above in the interlocking devices.

30 In the following description, when I use the term "switch" and give it a numeral, the same may be considered as a station, and is represented by a circle on the various views, and is mechanically or manually operated as shown on the various views to accomplish the desired condition.

35 Referring now more particularly to Figs. 16, 78 and 79 are the main line, or busses. In order to operate negative slide 4, switch 14' is closed, switches 15' and 16' are open, allowing 17' and 18' to control the limited movements of the negative slide out and in respectively; closing switch 14' shunts the circuit of electric switches 2', 7' and 8', and using only switches 3' and 4' as a controlling means in that circuit. The reversing of the 40 motor is controlled by a forward and reversing switch, illustrated as at 80 in Figure 16. To operate the bottom frame, switches 15' and 16' must be closed; switch 14' must be open, allowing switches 2', 3', 4', 7' and 8', to control this circuit. The same forward and reverse switch 80 is used for operating this frame. To operate the plate-holding frame 10, the switch 13' must be closed, switches 11' and 12' must be open, allowing 55 switches 9' and 10' to control the upper and lower limits, respectively, of that frame. By closing switch 13', the switches 1', 3', 5' and 6' are shunted, allowing this frame to be controlled switches 4' and 13', only in this 60 circuit. The up and down movements of this frame is controlled by a forward and reverse switch 80^a.

To operate the top frame, switches 11' and 12' must be closed, switch 13' must be open, 65 allowing switches 1', 3', 4', 5' and 6', to

control the movement of this frame. The movement of this frame in a forward or reverse direction is controlled by the forward and reverse switch 80^a.

I will now describe the switches and their 70 operation.

Switches 1' and 2' are alike; they are the index pin handle switches, as shown on Figure 11. This handle is attached to the screws 27 and 35, and revolves with them, and in 75 order to maintain a circuit while in operation suitable commutators 81 and 82, with brushes 81^a and 82^a, are provided, with stationary terminals 81^b and 82^b. Switches 3', 4', 5', 8', 9', 10', 11', 12', 13', 14', 15', 16', 17', 80 and 18', are constructed to open by the limit of movement of the moving parts to which they are attached, and while varying in the detailed construction, are old and substantially alike and may be seen in the various 85 views in more or less detail, and concerning which I claim nothing, per-se.

The switches 6' and 7' are attached to the locking means 39 and 30, and are closed upon the release of the locking means. Detail 90 is not shown, as I claim nothing concerning these particular switches in construction.

The switch 3' is attached to the plate-holding frame 10 and is opened by the cam carried by the top frame 17 as the plate-holding frame 10 descends. The switch 4' is attached to the pressure beam 43 and is opened by a cam attached to plunger 49 and is opened when the pressure head 47 descends. 95

Switch 5' is attached to the bottom frame 100 20, and is adapted to open at the limit of travel in either direction from the top frame 17 by the cams attached thereto.

Switch 6' is secured to the bottom frame 105 20 and is opened when the locking means 39 of the top frame 17 is closed.

Switch 7' is attached to table 1 and is opened when locking means 32 for the bottom frame 20 is closed.

A switch 8' is attached to table 1 and is 110 opened at the limit of travel in either direction of the bottom frame 20 by the cams attached thereto.

The switch 9' is secured to the plate-holding frame 10 and is opened by a finger, or 115 pin, attached to cam shaft 21 when the plate-holding frame 10 has reached the limit of its down position.

A switch 10' is secured to the plate-holding frame 10 and is opened by a screw attached to the bracket fastened to the top frame 17. This switch is opened when the plate-holding frame reaches its upward, or 120 top limit.

The switches 11' and 12' are operated by 125 the cam attached to the bar 85^a, as shown in Figure 10, and are opened when the plate-holding frame 10 is raised and lowered, and are closed when the top frame is operated.

Switch 13' is operated by a cam on the 130

bar 85^a, as shown in Figure 10, and is closed when the plate-holding frame 10 is raised and lowered, and is opened when the top frame is operated.

5 Switch 14' is operated in the same manner as switch 13', and is closed when the negative slide is operated longitudinally, either in or out, and opened when the bottom frame is operated.

10 The switches 15' and 16' are operated in the same manner as switches 11' and 12' and are opened when the negative slide is moved either in or out, and closed when bottom frame is operated.

15 A switch 17' is secured to table 1 and it is used for locking the negative slide in its printing position, and to stop the movement of the negative slide at the limit of its travel to its initial position.

20 A switch 18' is secured to the underside of the table 1 at a point near the central opening 3 and is opened when the negative slide reaches its printing position by means of a cam attached thereto.

25 Referring now to Figure 10, handle 71 is mounted on shaft 83, which shaft operates lever 84, operating sliding bar 85, sliding bar 85 operates to open various switches, as heretofore described. It also operates clutch 30 interlock 86 so that said clutch 74 is locked open when the sliding bar 85 closes switch 13' in one unit or 14' in the other unit, and opens switches 11' and 12' in one unit and switches 15' and 16' in the other unit.

35 The operation of my invention is as follows:

Assuming that the pressure head 47 and plate-holding frame 10 are up, bottom frame 20 is at the extreme limit of travel on the side opposite from its drive; top frame 17 is at the limit of its travel on either side, negative slide 4 is in its initial or non-printing position, and the light shutter 40 under the central opening 3 is closed.

45 The negative 6 is then placed in the negative slide in its proper position and securely fastened by the usual means, such as glueing the edges down with gummed paper to the glass plate. The negative slide is then moved 50 to its printing position by operating the motor through the forward starting switch and clutch 66. When it reaches the printing position over central opening 3, the limit switch 18' automatically cuts off the current 55 and stops the motor; the negative slide 4 is then locked at the limit of its movement by means of the hand lever 87.

When the hand lever 87 is in locked position the switch 17' is open, this preventing 60 the operation of the motor in a reverse direction. Switch 18' is opened when the negative slide 4 reaches its printing position and this prevents the operation of the motor in a forward direction. A sensitized plate is prepared and attached to the rubber-covered

plate-holding board by means of rubber cement, gummed paper or mechanical fastenings.

The plate-holding board 8 is now placed in the plate-holding frame 10 and locked in position by the locking means. Clutch 66 is released, and clutch 74 is engaged, index pin 96 and locking means 30 on the bottom frame 20 are released; bottom frame 20 is then op-

erated to a predetermined initial printing position by operating the motor through the reverse starting switch. Locking means 30 and index pin 96 are reengaged and the bottom frame 20 is then ready for printing. Clutch 74^a is then engaged, index pin 96^a, 70

and locking means 32, on top frame 17 are released, top frame 17 is then operated to the predetermined initial position by operating the motor through the forward or reverse starter switches, after which the index pin 96^a and locking means 32 are reengaged and the top frame 17 is then in position to print. Clutch 74^a is disengaged, and clutch 66^a is engaged, so as to lower the plate-holding frame 10 by operating the motor through the forward starting switch. The motor is automatically stopped when the frame reaches its proper position by a switch 9' and through a stopping means 98 mounted on cam shafts 21.

80 A switch 17' is secured to table 1 and it is used for locking the negative slide in its printing position, and to stop the movement of the negative slide at the limit of its travel to its initial position. Clutch 74^a is then engaged, index pin 96^a, 85 and locking means 32 are reengaged and the top frame 17 is then in position to print. Clutch 74^a is disengaged, and clutch 66^a is engaged, so as to lower the plate-holding frame 10 by operating the motor through the forward starting switch. The motor is automatically stopped when the frame reaches its proper position by a switch 9' and through a stopping means 98 mounted on cam shafts 21.

90 The plate is now in position to be printed on and is brought in intimate contact with the negative by means of the pressure head 47. A suitable light is placed under the central opening 3, and the light shutter 40 is manually opened to allow the light to act on the sensitized plate through the negative 6; and after a sufficient exposure has been made the light shutter 40 is closed and pressure head 47 released. The plate-holding frame 10 is then raised by operating the motor with the reverse starting switch and under similar adjustments lowered. The motor is stopped automatically at the limit of its upward movement by a switch 10'.

95 The index pin 96 and locking means 30 of the bottom frame 20 are then disengaged and the bottom frame is again moved to the next printing position by the means previously explained, after which operation the index pin 96 and locking means 30 are reengaged.

100 The plate-holding frame 10 is again lowered in the same manner as previously described, pressure head 47 is reengaged and light shutter 40 is opened and another print is made.

105 A series of prints are made until the full length of the plate is reached, it being necessary to go through the same routine for each print and when the last print is completed at the end of the plate and after light shutter 40 is closed the pressure head 47 is disengaged and plate-holding frame 10 raised. The top frame 17 is now operated by disen-

gaging index pin 96^a, locking means 32, and clutch 66^a.

5 Clutch 74^a is then engaged and top frame 17 operated by the motor through the forward or reverse starting switch to the next printing position. The index finger 96^a and locking means 32 are then reengaged. Clutch 74 is disengaged, clutch 66^a reengaged, and plate-holding frame 10 lowered, 10 as previously stated. The pressure head 47 is reengaged, light shutter 40 opened, and another line of prints is started. From now until the opposite end of the plate is reached, the bottom frame 20 is moved for 15 each succeeding printing position. When the end of the plate is reached, another step up is made by moving the top frame 17 after which the bottom frame 20 is used until the opposite end of the plate is again 20 reached, and these operations are repeated until the required number of prints have been made on the sensitized plate.

25 Should it be necessary to change the negative 6 while printing on the sensitized plate, the following operations are required:

30 Disengage the pressure head 47, raise plate-holding frame 10, disengage locking lever 87, freeing negative slide 4, disengage clutch 74, engage clutch 66, and operate motor through reverse starting switch. The switch 17' automatically stops motor when the negative slide 4 reaches the outside limit of its movement. The negative 6 is then 35 changed and the negative slide 4 returned to its printing position by operating the motor through the forward starting switch.

35 The motor is then automatically stopped by a switch 18' and the negative slide 4 has reached its printing position, as previously 40 described. The locking lever 87 is then reengaged, the plate-holding frame 10 lowered, pressure head 47 engaged, light shutter 40 is manually opened, and a print can again be made. These prescribed movements can only 45 be made when the respective mechanical and electrical interlocks are clear and when all interference to the operation of either of the units is properly eliminated, as heretofore fully described.

50 The operation of the top frame 17 and bottom frame 20 can also be reversed from that described, if found advisable.

55 After the required number of prints have been made on the sensitized plate, the top frame 17 and bottom frame 20 are returned to their initial positions, the plate-holding board 8 is removed and another sensitized plate attached thereto, after which it is again 60 placed in position and a duplicate plate printed from the same negative.

65 The negative 6 is only removed after a sufficient quantity of duplicate plates are printed from the original. When changing the negative 6 it is necessary to return the

negative slide 4 to its initial position in the manner heretofore described.

All the movements of the various units, as described, can also be manually operated if desired. The clutches operating these 70 units must, however, be disengaged and all interference eliminated, the same as required when operated by power.

The relative position of the plates and negatives when operated by power-driven 75 means may be finally adjusted by the manual operation. A most desirable feature where very accurate work is involved. The motors used in my operation, and as explained above, are of the ordinary reversing type, 80 and the forward and reverse starting switches are of the momentary contact type, so that the mechanism operates only when the switches are being manually held in contact. In larger motors the necessary starters, etc., are provided as is common in such practice, and concerning said starting switches, motors, and starters, I claim nothing, they being of the well known, ordinary 85 type.

90 Having thus described my invention, what I claim and desire to secure by Letters Patent is:

1. An organized printing device for multiplicity duplication, comprising a table, a 95 negative slide having a negative mounted thereon mounted for longitudinal travel on said table, electrical controlling means for moving said slide to a definite position, manual means for completing the movement of said slide, a plate holder, means for vertically operating said plate holder relative to said slide, said means being inoperative during the movement of the negative slide, and means for locking the negative slide 100 in fixed position whereby said plate holder may be moved.

2. An organized printing device for multiplicity duplication, comprising a table, a negative slide longitudinally movable on said 105 table, electrical controlling means for moving said slide to a predetermined position, manual means for completing the movement of said slide, a plate holding means superposed above said negative slide, electrical means controlling the movement of said plate holding means, said plate holding controlling means being inoperative when said negative slide is being operated, and means to control the movement of said plate holding means after said negative slide has been 110 properly positioned.

115 In testimony whereof he hereunto affixes his signature.

LOUIS H. ZEUN.
